B. Amge, Attorney

UNITED STATES PATENT OFFICE.

ICHIGORO NAKAHARA, OF TOKYO, JAPAN.

DENTAL ARTICULATOR.

1,272,985.

Specification of Letters Patent. Patented July 16, 1918.

Application filed January 15, 1917. Serial No. 142,543.

To all whom it may concern:

Be it known that I, ICHIGORO NAKAHARA, dentist, a subject of the Emperor of Japan, residing at No. 67, 2-Chome, Iida-Machi, 5 Kojimachi-Ku, city of Tokyo, Empire of Japan, have invented new and useful Improvements in Dental Articulators, of which the following is a specification.

This invention relates to a device which 10 will impart to the upper and lower jaws the proper registering motion so that a proper mold may be constructed for the fitting of artificial teeth, although this device may be used to correct the irregular motion of the 15 jaws with natural teeth.

It will be seen that this device in providing for a proper registering motion of the upper and lower jaws, a consequent proper registering of the upper and lower molds, 20 which are primarily inserted into the mouth and fitted over the upper and lower jaws of a patient, for the preparation of artificial teeth, will result.

In the accompanying drawing:

25 Figure 1 is a perspective view.

Fig. 2 is a similar view with the device in applied position.

In these views it will be seen that the reference numeral 1 designates a segmental 30 ring having its ends connected by means of a strap 2, which renders the ring 1 adjustable to the contour of the head of the patient. Provided on opposite sides of the ring are the outstanding lugs 3 and 3' provided with hook members 4, the hook portions of which extend below the lugs 3 and 3'. Secured to the ring 1 at 6 is a strap 5, adapted to extend around and engage the underside of the lower jaw of the patient, 40 and to engage the buckle 7 with its opposite end.

Secured to the ring 1 in a position corresponding to the location of the temples of the patient, are lugs 8 and 8' provided with 45 slots 16. Secured within the innermost of the slots 16 and adjustable both longitudinally and vertically therein, are supporting members 9.

50 Secured to the band 1 in a position directly above the nose of the patient, and adjustably mounted on such band 5 by means of the connection 11, is a rod 10 adapted to extend downwardly in front of the nose and below the lower jaw of the patient. A 55 transverse bar 13 carrying a jaw plate 12, in which the chin of the patient is adapted to

seat, is provided with end plates 18 formed with slots 19, through which rods 17 and 17', adjustably secured within the outermost slots 16 of the plate 8 are adapted to pass. 60 Secured to the bar 13 and extending directly outwardly therefrom, is a fork 13' adapted to embrace the rod 10. Secured to the lowermost portion of the rods 17 and 17' is a member 20 provided with a fork 21 65 adapted to engage the lowermost portion of the rod 10. Springs 14, 14', 15 and 15' are provided, adapted to be secured at one of their ends to a portion of the bars 13, and having their opposite ends secured to the 70 supports 9 and 4 respectively.

From the above it will be seen that to procure the proper results it is only necessary to place the band 1 around the patient's head and make the same conform to the 75 contour of the head by means of the strap 2, subsequently depressing the plate 12 and consequently the bar 13, to allow of the insertion of the patient's jaw or chin into the member 12, passing the strap 5 around the 80 underside of the lower jaw and securing the end thereof to the buckle 7. It will be seen that it would be impossible for the patient to take other than a correct bite, in view of the fact that all sidewise motion of the jaws 85 would be prevented by means of the engagement of the forks 12' with the bar 10. The immovable nature of the part 10 is due to its support by means of the connection 11 and engagement at its lowermost end with 90 the fork 24. It will be further noted that the slightest sidewise movement of the lower jaw is prevented by means of the rod 17 passing through the slot 19 and that further, the patient is free to make the proper 95 normal motion with his jaws, and that the springs 14, 14', 15 and 15' will always serve to keep the member 12 firmly in engagement with the chin of the patient.

Having now particularly described and 100 ascertained the nature of my said invention and in what manner it is to be performed I declare that what I claim is:

1. A device for preparing a model of a tooth-bite comprising a ring adapted to be 105 fastened on a patient's head, a guide rod on said ring, a jaw presser, springs connecting said jaw presser with said head ring, and a guide bar on said jaw presser coöperating with said guide rod for maintaining the 110 patient's jaws sufficiently straight.

2. A device for preparing a model of a

tooth-bite comprising a ring adapted to be fastened on a patient's head, a guide rod on said ring, a jaw presser, a guide bar projecting from the front of said jaw presser and coöperating with said guide rod for maintaining the patient's jaws sufficiently straight, and spiral springs connecting said jaw presser with said head ring.

3. A device for preparing a model of a tooth-bite comprising a ring adapted to be fastened on a patient's head, a guide rod on said ring, a transverse bar, a jaw presser supported on said bar, a guide bar projecting from the middle point of the said transverse bar and coöperating with said guide rod for maintaining the patient's jaws sufficiently straight, and spiral springs connecting said head ring with the ends of said transverse bar.

4. A device for preparing a model of a tooth-bite comprising an adjustable ring adapted to be fastened on a patient's head, a guide rod on said ring, a jaw presser, a guide bar on the front of said jaw presser, said guide bar and said guide rod coöperating for maintaining the patient's jaws sufficiently straight, vertical rods connected to said head ring, a connecting rod connecting the lower ends of said vertical rod, an additional guide bar on said connecting rod coöperating with said guide rod, and springs connecting said jaw presser to said head ring.

5. A device for preparing a model of a tooth-bite comprising a ring adapted to be fastened on a patient's head, a guide rod on said ring, a transverse bar, a guide bar on

the front of said transverse bar coöperating with said guide rod for maintaining the patient's jaws sufficiently straight, a jaw presser fixed on said transverse bar, projecting pieces fixed on said head ring, vertical rods fixed to said pieces, a connecting rod connecting the lower end of said vertical rod, an additional guide bar on said connecting rod coöperating with said guide rod, and springs connecting said transverse bar to said head ring.

6. A device for preparing a model of a tooth-bite comprising a ring adapted to be fastened on a patient's head, a guide rod on said ring, a transverse bar, a jaw presser on said transverse bar, a guide bar fixed on said transverse bar at the middle of the transverse bar, said guide bar coöperating with said guide rod for maintaining the patient's jaws sufficiently straight, projecting pieces fixed on said head ring and provided with small slots, vertical rods fixed in said slots, a connecting rod connecting the lower ends of the said vertical rods, an additional guide bar carried by said connecting rod and coöperating with said guide rod, said vertical rod passing through said transverse bar, and spiral springs connecting said head ring and said transverse bar.
